US0D1085913S

(12) **United States Design Patent** (10) **Patent No.:** **US D1,085,913 S**
(45) **Date of Patent:** **** Jul. 29, 2025**

(54) **CONTROL PAD FOR HEATING AND COOLING SYSTEM**

(71) Applicant: **SAMSUNG ELECTRONICS CO., LTD.**, Suwon-si (KR)

(72) Inventors: **Jihyeoung Lee**, Suwon-si (KR); **Minkyung Choi**, Suwon-si (KR); **Suhyun Yoo**, Suwon-si (KR)

(73) Assignee: **SAMSUNG ELECTRONICS CO., LTD.**, Gyeonggi-Do (KR)

(**) Term: **15 Years**

(21) Appl. No.: **29/883,905**

(22) Filed: **Feb. 4, 2023**

(30) **Foreign Application Priority Data**

Nov. 18, 2022 (KR) 30-2022-0047995

(51) **LOC (15) Cl.** **10-04**

(52) **U.S. Cl.**

USPC **D10/50**

(58) **Field of Classification Search**

USPC D10/30, 46, 50, 57, 62, 70, 71; D13/168

CPC F24D 3/146

(57) **CLAIM**

The ornamental design for a control pad for heating and cooling system, as shown and described.

DESCRIPTION

FIG. 1 is a front perspective view of a control pad for heating and cooling system, showing our new design;

FIG. 2 is a front view thereof;

FIG. 3 is a rear view thereof;

FIG. 4 is a left side view thereof;

FIG. 5 is right side view thereof;

FIG. 6 is a top plan view thereof;

FIG. 7 is a bottom plan view thereof; and,

FIG. 8 is a rear perspective view thereof.

The broken lines illustrating portions of the control pad for heating and cooling system form no part of the claimed design.

1 Claim, 8 Drawing Sheets
